SUBCALIBER ATTACHMENT FOR GUNS

James M. Dial, Dayton, Ohio.

Application February 8, 1946, Serial No. 646,399

13-Claims. (Cl. 42—77)

1

The present invention relates to portable firearms and more particularly to a subcaliber attachment for converting a normally large caliber weapon such as a shotgun into a small caliber arm such as a rifle.

Principal objects of the invention are to provide an attachment of the type indicated which will be simple and inexpensive to make, which will be capable of being installed and removed instantly and easily, which will be rugged in construction and durable and foolproof in use, which will be applicable to a wide range of shotgun types and kinds, which will unfailingly eject low caliber cartridge shells, regardless of whether the shotgun is provided with an ejector or whether the shot gun ejector is operating, which will be securely maintained in operative and predetermined aligned position in the shotgun barrel, which can be adjusted through a wide range of relative positions in the shotgun barrel to compensate for wear, misalignment of the bore, and sights, etc., and which will have numerous other and further advantages as will be evident from the present description and illustrations of an embodiment of the invention which I have made and tested in actual practice and which I therefore prefer and have selected to illustrate the principles of the invention.

In the accompanying drawing, which illustrates the preferred embodiment:

Figure 1 is a side elevational view of a shotgun in opened position, showing the subcaliber attachment in place with its ejector block manually extended;

Fig. 2 is a side elevational view, on a relatively enlarged scale, of the attachment;

Fig. 3 is a rear end elevational view of the attachment;

Fig. 4 is an axial sectional view;

Fig. 5 is a cross sectional view taken on the line 5—5 of Fig. 4;

Fig. 6 is a side elevational view of a tool used for withdrawing the attachment from the shotgun barrel; and

Fig. 7 is a cross sectional view taken on the line 7—7 of Fig. 2.

While the principles of the invention are applicable, without essential change, to numerous types and kinds of firearms, the invention is particularly useful for converting any type of shotgun into a small caliber rifle, and it is in this embodiment that the invention will be disclosed in the present application for Letters Patent.

In Fig. 1 a conventional type of shotgun is depicted in open condition by the reference

2

numeral 1; a portion of the stock being shown at 2, and 3 indicating a portion of the barrel. The attachment provided by the present invention is designated generally 4 and comprises a gunmetal barrel member having a rear portion 5 of cylindrical shape properly dimensioned to fit with slight clearance or play in the rear portion of the bore or the firing chamber of the shotgun with which the attachment is intended to be used. Continuous and integral with this rear portion is a forward portion 6, of reduced outside diameter. A continuous bore 7 extends axially through the entire barrel member and this bore may be rifled in the forward portion 6 and radially enlarged and shouldered in its rear portion to provide a firing chamber 8 for a small caliber cartridge 9, which may be a cartridge of standard .22 caliber.

The barrel member 4 is intended to be inserted axially into the shotgun barrel 3 from the rear or breech thereof, which can be readily done when the gun is in opened position, as shown in Fig. 1. To limit the penetration of the barrel member into the bore, the rear portion 5 of the barrel member is provided with a peripheral bead or enlargement 10 which seats against the rear face of the shotgun barrel in the same manner as does a shotgun shell of a caliber appropriate for the gauge of the shotgun.

As shown in Fig. 3, a segment of the bead or enlargement 10 is removed through an extent of somewhat less than 180°, or as much as may be necessary to avoid engagement of the bead 10 by the ejector or ejector finger (not shown) ordinarily provided on most shotguns. In a conventional type of double-barreled shotgun there are two such ejector fingers, or two portions of a single finger, one provided for each of the two barrels. In the double barreled shotgun 1 selected to illustrate the present invention, a single low caliber attachment is shown installed in the left barrel of the gun, and the bead 10 is removed around a portion of its right-hand and lower sides because it is this portion which is adjacent to the ejector finger or finger portion of such a gun. For use in single barreled shotguns, or guns having ejector fingers otherwise located, a different segment of the bead 10 will be removed, as will be readily understood.

The rear portion 5 of the barrel member 4 is recessed with an endwise opening 11, which may be of generally rectangular shape in cross section and extend forwardly into the member through a distance somewhat greater than the length of the low caliber cartridge 9 which the member is intended to receive. This recess opens

radially into the firing chamber 8 and contains an axially slidable ejector block 12 which has its upper surface cylindrically concavely curved as shown at 12a to supplement that part of the firing chamber 8 which is formed by the metal of the rear portion 5 and to cooperate with it to complete a chamber for the cartridge 9. The rear surface of the block is flush with the rear surface of the portion 5 and is radially extended at 13 to form a continuation of the bead 10 of the portion 5. It is this block bead 13 which is positioned to be engaged by the extractor provided on the gun, so that actuation of the extractor will pull the block 12 sufficiently back out of the recess 11, as to the dotted line position shown in Fig. 4, to eject a cartridge 9 from its position in the firing chamber.

The axis of the firing chamber is located eccentrically of the rear portion 5 of the barrel member, and the member is so mounted in the shotgun barrel that the firing pin (not shown) of the gun, which is arranged to strike the center of a shotgun shell, will strike a point on the rim of the low caliber cartridge 9. This arrangement is made necessary by the fact that most low caliber cartridges are of the rim-firing type and because it is this type of low caliber cartridge that is intended to be used in the present attachment.

The forward portion 6 of the attachment has an outside diameter which is considerably less than the inside diameter or bore of the shotgun barrel. This difference in diameters, combined with a slight difference between the outside diameter of the rear portion 5 of the attachment and the inside diameter or bore of the shotgun firing chamber in which the portion 5 is positioned, permits the attachment to be rocked slightly through an angular adjustment in the gun bore so as to vary the relationship of the axes of the attachment and the gun barrel. The relationship may be made variable between one of parallelism of the axes to one in which the axes are angularly separated in any direction sufficiently to compensate for any uneven wear of the shotgun bore or any imperfection of the gunsights. This makes it possible to mount the barrel member in the gun bore in such a way that the attachment axis will be properly related to the gunsights for accurate firing.

In order to calibrate the attachment by fixing the relative angle of the axes of the barrel member 4 and of the shotgun bore at any required correct value, the forward portion 6 of the barrel member is provided with a peripheral flange or enlargement 14 in which are set, at peripherally spaced intervals, a plurality of headed machine screws or studs 15. In the illustrated embodiment of the invention four such screws are used, at intervals of 90° around the flange 14. The head of each of these screws is provided with two, three or more small transverse holes through which a locking wire 16 may be passed. It will be evident that by turning the screws in their tapped openings in the flange 14 they may be individually set at any degree of radial projection and that all the screws may be locked in their positions by passing the single wire 16 through those of the holes in the screw heads which happen to be peripherally aligned. In setting the attachment for accurate firing, the barrel member is mounted in the shotgun bore with the screws 15 set at some trial adjustment. The gun is fired and any deviation causing the bullet to miss the target is noted. The attachment is removed and compensation is made to the right or left, or up or

down, by appropriately adjusting the screws 15. The gun is again fired and the adjusting operation repeated until accurate firing results. When this has been achieved, the several screws 15 are locked in position by the wire 16, and thus the proper relationship of the gunsights and the bore 7 of the barrel member 4 is maintained, regardless of any uneven wear of the shotgun bore and regardless of any misalignment of the gunsights with the shotgun bore.

In order to keep the inserted attachment securely mounted in the shotgun bore, I prefer to provide a leaf spring 17 which is bowed radially outwardly between the flange 14 and a boss 18 formed at the forward end of the rear enlargement 5. This spring may be held on the boss 18 by a small U-shaped clip 19 which is screwed to the boss and straddles the spring near its rear end, and the forward end of the spring is received in any one of a pair or more of radially spaced notches 20, 20 provided in the rear face of the flange 14. Fig. 2 shows in full and dotted lines how the spring 17 can be adjusted to project radially a greater or less extent and bear more or less forcibly against the lower portion of the shotgun bore so as to urge the forward portion 6 of the barrel member more or less firmly up against the upper portion of the shotgun bore.

For use in shotguns provided with an ejector, it is desirable to have the block 12 yieldably urged to its forward or inner position, so that on release by the ejector the block will move from its dotted line position of Fig. 4 inwardly to its full line position. For use in guns not provided with an ejector, or in guns having a broken or otherwise inoperative ejector, it is desirable to have the block 12 yieldably urged outwardly to its dotted line position of Fig. 4. In this way the cartridge 9 will be ejected automatically when the gun is broken to the open position shown in Fig. 1, and after a new cartridge has been inserted in the firing chamber while the block is thus rearwardly projected, the block will be restored to its forward position automatically, when the gun is closed, by the pushing force of the gun breech member 21 against the rearwardly projected block.

These alternative arrangements are provided by the simple mechanism which will now be described.

From the forward end of the block 12 a stem 22 projects through a rear guide bearing 23 and a forward guide bearing 24, which are spaced apart along a line parallel to the axis of the barrel member and radially down below the outer wall 55 of the reduced forward portion of the barrel member, although within the cross sectional area of the enlarged rear portion 5. The rear guide bearing 23 may be formed in what is in effect the front wall of the rear portion 5, and the forward guide bearing 24 may be formed in the boss 18. A coil spring 25 is wrapped around the stem between the two guide bearings, and a lug or stop 26 may be pinned to the extreme forward end of the stem 22, forwardly beyond the forward guide bearing 24. The function of this lug, which is square or otherwise polygonal in shape and is located so close to the barrel that it cannot turn, is to prevent such rotation of the stem 22 as might unscrew the stem from the block 12.

If it is desired to have the block 12 yieldably urged to forward position, the spring 25 is compressed between the rear guide bearing 23 and a pin 27 (Fig. 2) passed through a forward hole 28 (Fig. 4) formed through the stem 22. A washer 29 may be interposed between the pin 27 and the

spring, and it will be obvious that this spring, acting in tension between the pin 27 and the rear guide bearing 23, will yieldably urge the block 12 to its forward limit in which it is seated in the recess 11, in the full line position of Fig. 4.

If it is desired to have the block 12 yieldably urged rearwardly, to its dotted line position in Fig. 4, the pin 27 is removed from the opening 28 and inserted in a rear opening 30 (Fig. 4) formed through the stem 22 near the rear guide bearing 23. The washer 29 may be interposed between the pin in this position and the spring, which is now compressed between this pin and the forward guide bearing 24. The spring, under compression, urges the block 12 rearwardly to its dotted line position of Fig. 4, and this arrangement causes the block to eject the cartridge 9 automatically when the gun is opened to the position shown in Fig. 1, without reliance on any ejector finger.

It may be found desirable to protect the forwardly projecting end of the stem 22 by providing a sheet metal or stamped guard 31 to cover the end of the stem between the clip 19 and a point beyond the end of the stem where the guard can be fastened to the barrel member by a machine screw 32. This will prevent distortion of the stem in case the leaf spring 17 should become inwardly instead of outwardly bowed.

In order to facilitate extraction of the attachment from the bore of the shotgun in its convenient to form a more or less radial recess or hole 33 in the wall of the firing chamber opposite the slideable block 12. A hooked tool 34, shown in Fig. 6, may be inserted into the opening 33 so that the attachment can be readily withdrawn from the gun bore.

It is found in actual practice that with the spring 17 properly adjusted to press radially outwardly with appropriate pressure, the attachment is held in predetermined position in the shotgun bore and that it does not tend to rotate therein despite any amount of firing and rough handling. In this way the alignment of the attachment and gunsights to which the screws 15 have been adjusted is preserved.

After the attachment is withdrawn for any reason, as for example in order to use the gun bore for the firing of shotgun shells, the attachment can be unfailingly restored to the same position at which it was previously set in the gun bore by orienting the bead 10 and its cut-out segment in the same way as before with relation to the shotgun shell ejector. This is easily accomplished by taking care to set such a shoulder as is shown at 34, at one end of the cut-out segment, against the path through which the ejector or ejector finger moves. Any other reference point may be employed for assuring identical repositioning of the attachment after it has been properly adjusted and then removed, such, for example, as a line inscribed radially on the rear face of the rear portion 5 of the barrel member and a similar line inscribed on the rear face of the shotgun barrel. The attachment can then be set, by adjustment of the screws 15, with these two lines in registry or alignment, and it can always be repositioned to the same setting by replacing it in such a way that the two lines are registered or aligned.

It is believed that the essential principles of the invention will be clear to those skilled in the art from the foregoing description of a preferred embodiment. Other and further modifications of the invention are contemplated, and all of them,

to the extent that they embody the principles of the invention as pointed out in the appended claims, are to be deemed within the scope and purview thereof.

5 I claim:

1. A subcaliber attachment for the barrel of a gun comprising a barrel member receivable in the gun barrel, means provided at the rear end of the barrel member for limiting insertion thereof 10 in the gun barrel, and a plurality of peripherally spaced screws threaded into the barrel member forwardly of the rear end thereof and radially adjustable to engage the bore of the gun barrel to regulate the position of the barrel member axis relatively to the gun barrel axis.

2. A subcaliber attachment for the barrel of a gun comprising a barrel member receivable in the gun barrel, means provided at the rear end of the barrel member for limiting insertion thereof in the gun barrel, a plurality of peripherally spaced screws threaded into the barrel member forwardly of the rear end thereof and radially adjustable to engage the bore of the gun barrel to regulate the position of the barrel member axis relatively to the gun barrel axis, and means for holding the screws in adjustably selected positions.

3. A subcaliber attachment for the barrel of a gun comprising a barrel member receivable in the gun barrel, means limiting insertion thereof in the gun barrel, and resilient means projecting from one side of the barrel member against the adjacent surface of the gun barrel bore so as to urge the barrel member securely against an opposite portion of the gun barrel bore surface and tend to hold the barrel member in such position.

4. A subcaliber attachment for the barrel of a gun comprising a barrel member receivable in the gun barrel, means limiting insertion thereof in the gun barrel, and adjustable resilient means projecting in a generally radial direction from the barrel member into contact with the gun barrel bore so as to urge the barrel member of an adjustably selected pressure against an opposite portion of the surface of the gun barrel bore.

5. A subcaliber attachment for the barrel of a gun comprising a barrel member receivable in the gun barrel, a block slideable axially in the rear portion of the barrel member and cooperating therewith to form a subcaliber firing chamber, spring means urging said block forwardly in the barrel member, and a peripheral enlargement 55 formed on the rear end of the block adapted to be engaged by the ejector of the gun so that said ejector may slide the block rearwardly, against the action of the spring means, and withdraw a small caliber cartridge shell from the firing chamber.

6. A subcaliber attachment for the barrel of a gun comprising a barrel member receivable in the gun barrel, a block slideable axially in the rear portion of the barrel member and cooperating therewith to form a subcaliber firing chamber, a spring reacting between the block and the barrel member for urging the block forwardly in the barrel member and aligning the rear face of the block in the same plane as the rear face of the barrel member, and a projection formed on the block for cooperation with an ejector provided on the gun for sliding the block rearwardly against the action of the spring to withdraw a small caliber cartridge shell from the firing chamber.

7. The combination claimed in claim 6, including a stem forwardly extending from the block, a pair of spaced guide bearings for the stem formed on the barrel member, and a coil spring wrapped around the stem having its forward end fastened to the stem and having its rear end reacting in compression against the rearmost of the pair of guide bearings for urging the block forwardly in the barrel member.

8. A subcaliber attachment for the barrel of a gun comprising a barrel member receivable in the gun barrel and having a rear portion substantially the diameter of the gun firing chamber so as to make relatively snug fit therein and having a forward portion of reduced diameter, a radial enlargement formed on the rear end of the barrel member for limiting insertion thereof in the gun barrel, a peripheral flange projecting radially from the forward portion, and a plurality of peripherally spaced screws threaded into the forward portion at the zone of the flange thereof for radial adjustment to engage the bore of the gun barrel to regulate the position of the barrel member axis relatively to the gun barrel axis.

9. A subcaliber attachment for the barrel of a gun comprising a barrel member receivable in the gun barrel and having a rear portion substantially the diameter of the gun firing chamber so as to make relatively snug fit therein and having a forward portion of reduced diameter, a radial enlargement formed on the rear end of the barrel member for limiting insertion thereof in the gun barrel, a peripheral flange projecting radially from the forward portion, a plurality of peripherally spaced headed screws threaded into the forward portion at the zone of the flange thereof for radial adjustment to engage the bore of the gun barrel to regulate the position of the barrel member axis relatively to the gun barrel axis, and a wire inserted through holes in the heads of said screws to maintain them in predetermined radially adjusted positions.

10. A subcaliber attachment for the barrel of a gun comprising a barrel member receivable in the gun barrel, a block slidable axially between fixed limits in the rear portion of the barrel member and cooperating therewith to form a subcaliber firing chamber, a stem extending forwardly from the block, a pair of spaced guide bearings for the stem formed on the barrel member, a coil spring wrapped around the stem between the guide bearings, and means connecting the spring to the stem under compression between the stem and one of said guide bearings for urging the block against one of its fixed limits.

11. A subcaliber attachment for the barrel of

a gun comprising a barrel member receivable in the gun barrel, a block slidable axially between fixed limits in the rear portion of the barrel member and cooperating therewith to form a subcaliber firing chamber, a stem extending forwardly from the block, a pair of spaced guide bearings for the stem formed on the barrel member, a coil spring wrapped around the stem between the guide bearings, and means compressing the spring between the rear guide bearing and a point on the stem between the guide bearings so that the spring yieldably urges the block against its forward fixed limit.

12. A subcaliber attachment for the barrel of a gun comprising a barrel member receivable in the gun barrel, a block slidable axially between fixed limits in the rear portion of the barrel member and cooperating therewith to form a subcaliber firing chamber, a stem extending forwardly from the block, a pair of spaced guide bearings for the stem formed on the barrel member, a coil spring wrapped around the stem between the guide bearings, and means compressing the spring between the forward guide bearing and a point on the stem between the guide bearings so that the spring yieldably urges the block rearwardly to its fixed limit.

13. A subcaliber attachment for the barrel of a gun comprising a barrel member receivable in the gun barrel, a block slidable axially between fixed limits in the rear portion of the barrel member and cooperating therewith to form a subcaliber firing chamber, a stem extending forwardly from the block, a pair of spaced guide bearings for the stem formed on the barrel member, a coil spring wrapped around the stem between the guide bearings, said stem being provided with spaced holes between said guide bearings, and a pin insertable alternatively through any of said holes provided in the stem between the guide bearings, whereby the spring may be compressed between the rear guide bearing and the pin inserted in a forward hole to urge the block forwardly or between the front guide bearing and the pin inserted in a rear hole to urge the block rearwardly.
